(57) **CLAIM**

The ornamental design for a cordless peripheral for wireless data exchange, as shown and described.

DESCRIPTION

FIG. 1 is a perspective view of a cordless peripheral for wireless data exchange, showing a first embodiment of our new design;

FIG. 2 is a top view thereof;

FIG. 3 is a bottom view thereof;

FIG. 4 is a front view thereof;

FIG. 5 is a side view thereof, the other side view thereof being a mirror image;

FIG. 6 is a rear view thereof;

FIG. 7 is a perspective view of a cordless peripheral for wireless data exchange, showing a second embodiment of our new design;

FIG. 8 is a top view thereof;

FIG. 9 is a bottom view thereof;

FIG. 10 is a front view thereof;

FIG. 11 is a side view thereof, the other side view thereof being a mirror image; and,

FIG. 12 is a rear view thereof.

No pattern, texture, or color are claimed in association with the fine stipple shading (stippling) figurative effects in FIGS. 1-6 or the linear shading figurative effects in FIGS. 7-12. The figurative effects portray various illusions (e.g., varying degrees of surface shadow, or surface highlights), meant to distinguish the nature of various areas (e.g., as solid vs. open, and their direction and degree of curvature, if any), and thereby clarify the character and contour of all surfaces of any 3-dimensional aspects of the design. In FIGS. 1-12, broken lines and unshaded portions contained within broken lines depict portions of the cordless peripheral for wireless data exchange that form no part of the claimed design. Perspective views are not drawn to scale.

1 Claim, 4 Drawing Sheets
